US0D1014670S

(12) **United States Design Patent** (10) **Patent No.:** **US D1,014,670 S**
(45) **Date of Patent:** **** Feb. 13, 2024**

(54) **EXERCISE BAND**

(71) Applicant: **Fitbeat Australia Pty Ltd.**, Rose Bay (AU)

(72) Inventor: **Michael Vernon Kunitz**, Rose Bay (AU)

(73) Assignee: **FITBEAT AUSTRALIA PTY LTD**, Rose Bay (AU)

(**) Term: **15 Years**

(21) Appl. No.: **29/818,101**

(22) Filed: **Dec. 7, 2021**

(30) **Foreign Application Priority Data**

Jun. 9, 2021 (AU) 202113433

(51) **LOC (14) Cl.** **21-02**

(52) **U.S. Cl.**

USPC **D21/692**; D21/662; D21/682

(58) **Field of Classification Search**

USPC D21/662, 677, 682, 683, 684, 685, 692, D21/694

CPC A63B 21/0552; A63B 21/0555; A63B 23/1209; A63B 21/00185; A63B 21/028; A63B 23/0355; A63B 21/045; A63B 23/03516; A63B 69/0062; A63B 21/018; A63B 21/065; A61H 11/00

(57) **CLAIM**

The ornamental design for exercise band, as shown and described.

DESCRIPTION

FIG. 1 is a left side view, in a first embodiment;

FIG. 2 is a front view thereof;

FIG. 3 is a right side view thereof;

FIG. 4 is a back view thereof;

FIG. 5 is a perspective view thereof;

FIG. 6 is a perspective side view thereof;

FIG. 7 is a perspective side view thereof;

FIG. 8 is a perspective side view thereof;

FIG. 9 is a top view thereof; and,

FIG. 10 is a bottom view thereof.

1 Claim, 10 Drawing Sheets
